DESIGN.

M. L. NADLER.

QUILT.

APPLICATION FILED MAR. 19, 1917.

50,954.

Patented June 19, 1917.

Inventor

MAURICE L. NADLER

By his Attorney

Maurice Nadler

UNITED STATES PATENT OFFICE.

MAURICE L. NADLER, OF NEW YORK, N. Y.

DESIGN FOR A QUILT

50,954.

Specification for Design. Patented June 19, 1917.

Application filed March 19, 1917. Serial No. 155,956. Term of patent 7 years.

To all whom it may concern:

Be it known that I, MAURICE L. NADLER, a citizen of the United States, residing at New York city, in the county of New York and State of New York, have invented a new, original, and ornamental Design for Quilts, of which the following is a specification, reference being had to the accompanying drawing, forming part thereof.

The figure is a plan view of a quilt, showing my new design.

I claim:

The ornamental design for a quilt, as shown.

MAURICE L. NADLER.

Witnesses:

REUBEN KIRSCHSTEIN,
SOPHIE HOROWITZ.
